UNITED STATES PATENT OFFICE.

EDWIN C. SHERWIN, OF BRANDON, WISCONSIN, ASSIGNOR OF ONE-HALF TO EDGARTON H. SHERWIN, OF BRANDON, WISCONSIN.

ROAD-GRADEER.

No. 874,916.

Specification of Letters Patent.

Patented Dec. 24, 1907.

Application filed April 11, 1907. Serial No. 367,622.

To all whom it may concern:

Be it known that I, EDWIN C. SHERWIN, citizen of the United States, residing at Brandon, in the county of Fond du Lac and 5 State of Wisconsin, have invented certain new and useful Improvements in Road-Graders, of which the following is a specification.

This invention contemplates certain new 10 and useful improvements in grading machines for use in grading country roads, in smoothing rough or rutty roads, in keeping in first class condition for travel all grades that have been already formed, in cleaning 15 out gutters in cities and villages, or grading lawns around new buildings or the like, and in general wherever it is required to move dirt a short distance.

The invention has for its object an improved construction of road grader of the 20 sulky or riding type in which the cutting or scraping blade is movable or adjustable relatively to the sulky, in which the sulky is kept always in line with the main tongue so as to 25 allow the blade to play up and down freely and permit either end of the blade to be raised or lowered independently of the other, and which holds the blade to its work by preventing it from sliding sidewise, for with my 30 improved construction of road grader, none of the weight of the sulky is imposed upon the blade. The blade with its attachments is made heavy enough to do the work, and the entire weight of the sulky and operator prevents 35 any slipping of the machine, which avoids that serious fault with most road graders in the construction of which, in order to get sufficient weight on the blade to make it cut into the ground, a part or all of the 40 weight of the sulky is imposed upon the blade, thereby leaving little or no weight on the wheels, with which to prevent sliding.

With this and other objects in view as will 45 more fully appear as the description proceeds, the invention consists in certain constructions, arrangements and combinations of the parts which I shall hereinafter fully describe and then point out in the appended claims.

For a full understanding of the invention 50 and the merits thereof and also to acquire a knowledge of the details of construction of the means for effecting the result, reference is to be had to the following description and 55 accompanying drawings, in which:

Figure 1 is a rear perspective view of a road grader embodying the improvements of my invention. Fig. 2 is a longitudinal sectional view thereof. Fig. 3 is a rear elevation. Fig. 4 is a detail perspective view of 60 one of the quadrants. Fig. 5 is a detail sectional view illustrating the detent engagement of a hand lever with a quadrant. Fig. 6 is a detail view of a portion of the plate and its foundation block. 65

The blade 1 of my improved road grader is preferably formed of steel of the required length, width and thickness, which is sharpened at its lower edge, said edge being curved forwardly so as to impart to the blade a turning edge or surface similar to the plow. This, in addition to the angle at which the blade is set, keeps the dirt in a continual sliding movement when the machine is in operation and prevents all clogging. The blade 1 is bolted 70 or otherwise secured to a casting or foundation block 3 which is of considerable weight, and which is tapered from its front end towards its rear end, so that the greater part of its weight is thrown on that end of the blade 75 80 which does the digging.

The foundation block 3 is formed with a preferably integral casting 4 which extends at an oblique angle to the foundation block 3, although being located, when the parts are 85 assembled, in the median plane of the machine. This casting 4 is strongly braced and is formed at its upper edge, with a laterally widened seat 5, so as to constitute a supporting bracket for the rear end of the main 90 tongue 6. This tongue is preferably formed of two angle metal straps 7 to the horizontally extending portions of which a base plate 8 is riveted, and the rear end of this main tongue is bolted or otherwise rigidly secured to the bracket constituted by the casting 4 with its laterally widened seat 5. 95

The sulky or riding support for the weighted grading blade comprises traveling wheels 9 that are journaled on stub axles 10 and 100 having bearings within depending hangers 11 secured at their upper ends to the axle 12. This axle is constructed of comparatively wide steel channel bars so as to provide a box which may be weighted, if found necessary, 105 in order to augment the weight of the driver so as to prevent the machine from sliding sidewise when the blade is carrying a large amount of soil. To the bottom of this axle 12 a tongue 13 is secured, said tongue con- 110

sisting of an inverted channel steel strip which is coupled to the main tongue at about the center of the latter by a pivot or bolt 14. The base of the sulky tongue 13 carries at its 5 rear end the seat spring 15 and said rear end passes through a vertically extending steel arch guide 16, which is bolted or otherwise secured to the base of the main tongue 6. 17 and 18 designate braces, the brace 17 being secured to the sulky tongue and to the axle 12; and the other brace 18 being secured to the main tongue and to the foundation block 3 near the front end of the latter.

The blade and its foundation block are 15 provided with suspension chains 19 near the ends, and said chains are in turn connected to the short arms of bell crank hand levers 20 that are fulcrumed on quadrants 21 rigidly secured one to the end of the axle 12 and the 20 other to a bracket attached to axle and which are provided with ordinary detents to engage the toothed surface of said quadrants. One of the wheels 9 is located at the rear of the blade and the other in front, and there is ample room left between this last named wheel 25 and the blade to allow any amount of soil that the blade will carry to pass through without clogging. The position of the wheels so balances the machine that there is no un- 30 due weight imposed upon the necks of the horses.

By means of the hand levers 20, the blade may be raised or lowered and be adjusted to any position desired.

35 From the foregoing description in connection with the accompanying drawings, it will be seen that I have provided a simple, durable and efficient construction of road grader in which the sulky is entirely independent of 40 the blade, that is, there can be none of the weight of the sulky imposed upon the blade. This is an important feature of my invention and one in which the arched guide 16 plays an important part, as the said arch keeps the 45 sulky in line with the main tongue, and allows the blade to play up and down freely and permits either end of the blade to be raised or lowered independently of the other, as well as holding the blade to its work by 50 preventing it from sliding sidewise. The blade with its attachments is made heavy enough to do the work, thereby avoiding a serious fault which is incident to most graders of the sulky type, in which, in order to obtain 55 sufficient weight on the blade to make it cut into the ground, it is necessary to throw part or all of the weight of the sulky upon the blade, thus leaving little or no weight on the wheels with which to prevent sliding. Hence 60 when this is done, the machine slides away from its work and nothing is accomplished. With my invention this is impossible, as the entire weight of the sulky and operator tends to prevent any sidewise sliding movement 65 and if the weight of the sulky and operator is

not sufficient, the requisite weight may be provided by simply weighting the steel box which is constituted by the channel iron axle 12.

It is of course understood that the machine may be used with two, three or four horses, the main tongue being arranged for lengthening at the point, when more than two horses are used.

Having thus described the invention, what is claimed as new is:

1. A road grader comprising a blade, a main tongue from which said blade is directly suspended, a sulky provided with a tongue having a loose connection with the main tongue, a guide secured to the base of the main tongue and guiding the sulky tongue in relatively vertical movement between the two tongues, and suspension means from the sulky to the blade. 85

2. A road grader comprising a blade, a main tongue to which the blade is rigidly connected, a sulky provided with a tongue loosely connected at its front end to the main tongue, the main tongue being provided with a vertically extending arched guide, which embraces the rear end of the sulky tongue, independently movable hand levers fulcrumed on the sulky, and suspension chains connecting said levers with the 95 blade. 90

3. A road grader comprising a blade adapted to be held in a plane oblique to the length of the machine, or direction in which it is adapted to travel, a foundation block to 100 which said blade is secured, said block acting in a capacity of weight in the blade and being thicker at its front end than at its rear end, whereby to impose a greater amount of its weight on the cutting end of the blade, 105 said foundation block being formed with a rearwardly extending bracket, a main tongue secured at its base to the bracket, and a sulky provided with means for raising and lowering the blade and having a relatively 110 vertical movement with the tongue, as and for the purpose set forth.

4. A road grader comprising a blade, a main tongue to which said blade is secured, a sulky provided with a tongue having a loose 115 connection with the main tongue, a guiding connection between the bases of the two tongues, said sulky including an axle in the form of a box, whereby weights may be disposed in said box, for the purpose specified, 120 and hand levers fulcrumed on the sulky and having suspension connections with the blade.

5. A road grader comprising a blade, a main tongue to the base of which said blade 125 is rigidly connected, said tongue being provided at its base with an upwardly extending arched guide, a sulky comprising traveling wheels located one in the rear and the other in front of the blade and also compris- 130

ing an axle supported by and connected to the traveling wheels and constructed of channel stuff forming a box adapted to be weighted, a tongue rigidly secured to said axle and loosely connected at its front ends to the main tongue, the rear end of the sulky tongue extending through and snugly fitting the arched guide, independently operable hand levers fulcrumed on the sulky, and suspension chains connecting said hand levers with the blade near the ends of the latter.

6. A road grader comprising a blade, a main tongue to which said blade is secured, a sulky provided with a tongue having a loose

connection with the main tongue, a guiding connection between the rear ends of the main tongue and sulky tongue, levers fulcrumed on the sulky and flexible connections between said blade and said levers, and adapted to permit the entire weight of the blade to be imposed upon the ground, independently of the weight of the sulky.

In testimony whereof I affix my signature in presence of two witnesses.

EDWIN C. SHERWIN. [L. S.]
